UNITED STATES PATENT OFFICE.

GEORGE TILLMAN SHELEY, OF INDIANAPOLIS, INDIANA.

PENCIL CLIP AND ERASER HOLDER COMBINED.

Application filed December 3, 1924. Serial No. 753,669.

My invention relates to pencil clips and eraser holders combined, which may be manually attached and removed from standard pencils, as desired, and more particularly to devices of this class, having a rubber holder and clip, integrally combined, and consists substantially in the construction, combination, and arrangement of parts hereinafter set forth and pointed out more particularly in the claims.

An object of my invention is to provide a pencil eraser holder and clip combined, which may be readily attached to a standard pencil, and taken off when desired for purpose of being attached to another pencil, whereby the same device may be used during the life of a number of pencils.

It is a primary object of my invention to provide a device of this class having an ample supply of erasing material, which may be fed outwardly in magazine manner, when desired, whereby, an eraser worn away from use, may be extended outwardly accordingly, and thus avoid the necessity of using an inconvenient short bit thereof.

It is a further object of my invention to provide a magazine contained eraser in addition to the eraser actually exposed to use, whereby the worn eraser may be displaced with the magazine carried eraser, when desired.

It is a further object of my invention to provide a combined rubber holder and a pencil clip, having a tubular structure adapted to contain the rubber holder, whereby the manual insertion of the holder in said tubular structure will lock the eraser in said holder.

The above and other objects are attained by the structure illustrated in the accompanying drawings, in which Figure 1 is an actual sized view of my device shown attached to a standard pencil; Fig. 2 is an enlarged fragmentary and partly sectional view drawn somewhat as an elevation of Fig. 1; Fig. 3 is a detailed view showing the eraser and the holder for same; Fig. 4 is a detailed elevation of said holder; and Fig. 5 is a sectional view taken on line 5-5 of Figure 2.

Similar characters of reference designate similar parts throughout the several views. Referring to Fig. 1, the numeral 1 designates a standard pencil to which my device is attached; 2 designates a barrel to which the fixed termination of the clip 3 is attached.

Formed on the lower end of said barrel below the point of attachment to said clip is a split tubular construction 4, which is constructed of spring material and tensioned inwardly against the pencil 1, by which arrangement the device may be manually forced and retained on said pencil, and likewise removed, the free end 5 of the clip 3 being disposed close to said pencil in a conventional manner, whereby the device considered as a whole may be retained in the carrier's pocket, the edge of which is confined between said pencil and said clip, as understood by those familiar with the art, said clip being also conventionally constructed of spring material, so that it may be engaged with the pocket edge by manually forcing said edge between said pencil and said clip, by which said clip will springingly yield to receive same, the extreme lower point of said clip being conventionally flared in order to receive pocket material of different thicknesses.

The rubber eraser 6 is of cylindrical character and is contained in its holder 7, the upper end of said rubber being exposed for use in typical manner.

I have noticed that in many instances such erasers are worn entirely out or inconveniently short before the pencil or the holder are worn out, and I have therefore provided an extra eraser 8 to be carried along in the lower part of the holder 7, for use when the eraser 6 has been nearly worn out, it being convenient to push the eraser 6, out further by manual upward pressure against the extra eraser 8. The lower portion of said holder and said extra eraser are firmly disposed within the upper portion of the barrel 2, and I have constructed the lower portion of said holder in split manner whereby the insertion of same in said barrel will spring itself in tightly against said eraser or extra eraser, or both. As the eraser being used is constantly being worn out and thus being made shorter, it is desirable to push it out occasionally to correspond with such wear.

The split portion of the holder 7, is somewhat divided from the exposed or upper portion of same by the transverse slot 9, the vertical split 10 being adapted to open into said slot. By this arrangement the clamping, or lower portion of said holder may be actuated without disturbing the upper or more exposed portion of said holder. In

- constructing said slot and said split in this manner, the corners 11 are formed at the junction thereof, which are bent slightly inwardly, and thus adapted to serve as teeth 5 for engaging the erasers 6 and 8 more firmly, especially when said holder is manually contained in said barrel, being sprung somewhat out of such engagement when said holder is removed.
- 10 A bead-like shoulder 12 is provided on the holder 7, near the upward extremity thereof, it being convenient for said holder to be normally inserted down in the barrel 2 until said shoulder embraces same. Said shoulder thus serves as a stop for restricting the inserting movement, and also serves as a finger grasp, or fingernail hold when removing said holder.

I preferably locate the transverse slot 9 just below the shoulder 12, said slot being disposed at a comparatively high point on said holder, but still normally in and concealed by the barrel 2, when the apparatus is assembled. By this arrangement the teeth 25 forming corners 11 are likewise located upwardly on said holder. This is advantageous as the erasers 6, being made shorter by use and correspondingly moved upwardly, will, even when rather short be engaged by 30 said corners.

The lower portion of the holder 7 is considerably cut away in quill manner, having a feathered characteristic, which renders same easy to enter in the barrel 2.

35 The upper extremity of the barrel 2 is beveled at points 13, which gives greater access to the shoulder 12 when removing said holder.

As above described the split tubular construction 4 is constructed of spring material and tensioned inwardly against the pencil 1. With this in view I have provided open spaces 14 in said construction to lessen and soften the tension thereof.

45 The ends of the transverse slot 9 are somewhat enlarged which improves the spring characteristic of same in the region of the corners 11.

The vertical slot 15 communicates at its 50 upper extremity with the V shaped slot 16 forming a V shaped opening therewith, by which arrangement the split construction 4 may springingly actuate as above mentioned into contact with the pencil 1, without correspondingly springing the other portions of the barrel 2.

While I have illustrated in a general way, certain instrumentalities which may be employed in carrying my invention into effect, 60 it is evident that many modifications may be made in the various details, without departing from the scope of the appending claims, it being understood that my invention is not restricted to the particular forms herein described.

I claim as my invention:

1. A device comprising a hollow member, one end of which has a spring tension for gripping the normally upper end of a conventional lead pencil when the pencil is entered therein, the other end of said member being tubular; an eraser holder adapted to snugly fit said tubular end, said eraser holder having outwardly sprung portions adapted to be forced inwardly in engagement with 75 an eraser means contained in said holder when the holder is entered into said hollow member, said holder having an opening in its normally lower end, thru which added pieces of eraser material are inserted as the 80 normally upper eraser portion is worn off.

2. A device comprising a tubular member, one end of which has a spring tension for gripping the normally upper end of a conventional lead pencil, when the pencil is entered therein, an eraser holder adapted to snugly fit and be removably contained in said tubular member; outwardly sprung yielding corners adapted to be forced inwardly and held in contact with an eraser 90 means insertable in said holder when the holder is entered in the tubular member, said holder having an opening in its normally lower end thru which pieces of eraser material are assembled in place from within 95 toward the wearing eraser portion, and a shoulder means acting to restrict such inserting movement and serving as a fingernail hold in removing said holder.

3. A device comprising a tubular member, one end of which has a spring tension for gripping the normally upper end of a conventional lead pencil, an eraser holder adapted to be entered in said tubular member, yielding corners thereon adapted to be 105 engaged by said hollow member and forced inwardly in contact with an eraser means insertable in said holder from within, when the holder is entered in the tubular member, a shoulder means normally serving to 110 locate said holder in said member, and act as a finger-nail hold in removing said holder, a clearance being formed on the normally upper end of said tubular member, whereby 115 access to said shoulder may be readily had, when removing said holder.

4. A device comprising a member, one end of which has a spring tension for gripping the normally upper end of a lead pencil, the other end of said member being hollow; an eraser holder snugly fitting the hollow portion of said member, outwardly sprung yielding parts on said holder adapted to be forced inwardly in contact with erasing material insertable in said holder from within, when the holder is forced into the hollow portion of the first member, said holder serving to contain conventional erasing material in its normally upper end, and also extra erasing material under the first mentioned 120 125 130

erasing material, to replace same when worn out, and be supplied by outward movement from within.

5. A device comprising a member, one end 5 of which has a spring tension for gripping the normally upper end of a conventional lead pencil, the other end of said member being tubular, and an eraser holder slidably and removably contained in the tubular portion 10 of said member and snugly fitting therein, said holder being slotted, and the edges of the slotted portions expanded outwardly; corners on said slotted portions adapted to be forced inwardly in contact with an eraser 15 means insertable in said holder from within, when the holder is entered into the tubular portion, said holder serving to contain a conventional eraser in its normally upper end, and also extra erasing material under 20 said eraser, adjacent thereto to replace same when worn out, the first eraser being fed outwardly when worn away by manually raising said extra erasing material against same, whereby said erasing material forms 25 an adjustable bottom for said eraser, and is manually raised from within to be used in the place of said first eraser.

6. A device comprising a tubular member, one end of which has spring tension for 30 gripping the normally upper end of a lead pencil, an eraser holder snugly fitting and normally contained in said tubular member, said holder having slightly outwardly flared portions, and teeth means formed on the outwardly flared portions of the holder adapted 35 to be sprung into engagement with an eraser means contained in said holder, when said holder is inserted in said tubular member, said teeth means being normally contained 40 within and concealed by said tubular member.

7. A device of the class described, com-

prising a hollow member adapted to contain the normally upper end of a conventional writing pencil; and an eraser holder 45 adapted to be contained in the normally upper end of said hollow member, said eraser holder having a split construction adapted to be sprung into firm engagement with an eraser held thereby, by inserting 50 said holder in said hollow member, the normally lower end of said holder being quill shaped, whereby it may be readily entered in said hollow member, and whereby the eraser held thereby may be inserted thru 55 said normally lower end, toward the normally upper end and thence into use, said split construction being normally contained in and concealed by said member.

8. A device of the class described comprising a hollow member adapted to contain the normally upper end of a conventional writing pencil; and an eraser holder adapted to be contained in the normally upper end of said hollow member, said eraser holder having a normally horizontal slot, and a normally vertical split, the upper end of which communicates with said horizontal slot, whereby said holder is adapted to be sprung into firm engagement with an eraser held 60 thereby, by inserting said holder in said hollow member, without correspondingly springing the normally upper portion of said holder, whereby said slot and split are normally contained within said member, the 65 normally exposed part of said holder being smooth and neat in appearance, said eraser being added to as used by movement of additional erasing material outwardly from the normally inwardly contained eraser holder. 70 75 80

In testimony whereof, I have hereunto set my hand on this the 22nd day of November, 1924, A. D.

GEORGE TILLMAN SHELEY.
